TIMEKEEPER

Gaston Victor Georges Cusin, Paris, France, assignor to Cartier, Inc., New York, N. Y., a corporation of New York

Application January 17, 1940, Serial No. 314,316
In France June 17, 1939

21 Claims. (Cl. 58—2)

The present invention relates to time keepers, such as clocks, watches, wrist-watches, and the like.

The object of the invention is to provide an apparatus of this kind the clockwork of which is invisible.

In the case of a clock, according to the invention, the whole of the vertical shafts and of the pieces for transmitting the movement to the hands (if the clockwork mechanism is housed in the base of the clock), or the whole of the mechanism itself (which is then vertically arranged) is fitted inside a glass body or a body of an analogous transparent material, the vertical walls of the housing of said clockwork being so disposed as to ensure a total reflection of the visual rays from a person located in front of the clock or substantially so.

This body will be provided, in its front part, with a vertical slot of very small size for the passage of the spindle carrying the hands of the clock, and this front face will constitute the dial of the clock. With such an arrangement, the clockwork is wholly invisible and the clock has a mysterious character.

According to an embodiment of the invention, parallel vertical mirrors, or metallic surfaces are provided in the housing of the clockwork in order to reflect the visual rays having a certain inclination, that is to say corresponding to a person located on the side of the clock. For instance, the mechanism may be enclosed in a metallic casing of hexagonal section.

The body may be constituted by juxtaposition of two or four elements or prisms of glass providing, as well at the front as at the rear, between the total reflection faces, a very thin slot, the elements being secured together by means of a small bar or stirrup which simultaneously hides the slots.

In the case of a watch, the movement will be wholly disposed between two narrow support plates, including the mainspring, the system of total reflection prisms being made of blocks in the form of substantially semi-circular sectors or the like, in such manner as to form, once they are assembled together, a perfect circle. The whole is kept rigidly assembled by means of a fixation ring. The winding up and the resetting to the correct time can be effected either by means of a winding up knob or by means of keys inserted for this purpose in the face opposed to the dial.

In the case of a wrist watch, the clockwork will be as above described but it is no longer

necessary to make use of four total reflection prisms, since the opposed face of the system, with respect to the dial, is in contact with the skin. The whole of the two prisms and of the clockwork may be fitted in a box of glass or another transparent material and be maintained therein by means of two lugs serving also as a means for the fixation of the wrist band through which the watch is held.

Other features of the present invention will result from the following detailed description of some specific embodiments thereof.

Preferred embodiments of the present invention will be hereinafter described, with reference to the accompanying drawings, given merely by way of example, and in which:

Fig. 1 is a perspective view of a clock made according to a first embodiment of the present invention;

Fig. 2 is a profile view corresponding to Fig. 1, with the glass body removed, showing the clockwork mechanism;

Fig. 3 is a partial front view of the device of Fig. 2;

Fig. 4 is a front view of the clock, the external casing or box being supposed to be removed;

Fig. 5 is a vertical and transverse section of the clock on the line V—V of Fig. 4, the external casing being in position;

Fig. 6 is a horizontal section of the clock on the line VI—VI of Fig. 4;

Fig. 7 is a diagram showing the path followed by the visual rays through the prisms of the device;

Fig. 8 is a front view, showing another embodiment of the clockwork mechanism;

Fig. 9 is a profile view of the clockwork shown by Fig. 8;

Fig. 10 is a front view of a mysterious watch made according to the present invention;

Fig. 11 is a back view corresponding to Fig. 10;

Fig. 12 is a view on an enlarged scale on the line XII—XII of Fig. 10;

Fig. 13 is a front view of a wrist watch according to the invention;

Fig. 14 is a side view of the wrist watch according to Fig. 13;

Fig. 15 is a back view of the wrist watch of Figs. 13 and 14;

Fig. 16 is a sectional view on an enlarged scale on the line XVI—XVI of Fig. 13.

In the embodiment shown by Figs. 1 to 6, the clock includes a base 1 constituted (Fig. 2) by two plates 2—3, between which is housed the clock-

work 4. The pinions for driving the spindle which carries the hour hand 5 and the spindle which carries the minute hand 6 are connected to said spindles through two shafts 5a and 6a, provided at their upper ends with two pinions 7 and 8 meshing with pinions 9 and 10, respectively rigid with said spindles.

The shafts 5a and 6a are supported by two plates 11 and 12, rigid with the upper plate 2 of base 1. The winding up and resetting to the correct time are performed by means of key 13 and knob 14, located on the under side of the lower plate 3.

As shown by Fig. 3, the space occupied by the part of the mechanism which projects from the base, as seen from the front, is reduced to a minimum. This part of the mechanism is then housed in the free space left by the juxtaposition of four prisms 15, 16, 17, 18, the inclined faces of which, such as 15a, 16a, are of the total reflection arrangement. These prisms are located as shown by Figs. 4, 5 and 6 above the base of the clock. These prisms 15, 16, 17 and 18 are rigid with the base, on the one hand through the medium of a stirrup-shaped bar 19 screwed on plate 2 and on the other hand through a casing 20 which surrounds the whole of the prisms and the base and can be fixed to the side of the base through small screws.

Ahead of the body formed by the prisms there is provided a protection glass 21 (Fig. 5). The dial 22 of the clock is, for instance, welded or riveted to bar 19 at points P and P₁. Said bar is finely polished so as to increase the feeling of continuity.

Furthermore, I can provide, in the housing of the glass body, either mirrors or a polished casing 23, preferably of octagonal section, intended to hide the part of the mechanism which is located above plate 2, as shown by Fig. 6.

Under these conditions, and as shown by Fig. 7, it is clear that the extreme visual rays a, a₁, which are perpendicular, or substantially perpendicular, to the glass body, extend therethrough, while the rays such as b close to the center of the clock are reflected by faces 16a, 15a, as indicated at b₁. As for the very inclined rays, such as c, they are reflected on the mirror or the parallel faces 23a of the casing which surround the clockwork or portions of said clockwork, as shown by arrow c₁. In any case, the mechanism is wholly invisible, whatever be the direction from which the dial of the clock is looked at.

The same reasoning applies to the visual rays directed in the opposite direction. In other words, the same curious effect is obtained when the clock is seen from the back as when it is seen from the front.

In the embodiment shown by Figs. 8 and 9, only mainspring 24 is housed in the base of the clock, between plates 2 and 3. The remainder of the clockwork is arranged within a volume of elongated shape in the vertical direction, between two narrow plates or uprights 11a, 12a.

The winding up is effected by means of key 14a, which is engaged into the slot formed by the small space existing between prisms or elements 17 and 18.

In the embodiment shown by Figs. 10 to 12 inclusive, the watch according to the invention includes a clockwork 25 which is enclosed inside a metallic casing 26 which will preferably be finely polished and around which are mounted four total reflection prisms 27, 28, 29 and 30, of substantially semi-circular shape. Above prisms 27, 28, is

placed the dial 29a which serves to preserve space 29b in which hands 31 and 32 are housed. On both of the faces of the watch, two glass plates are provided, one 33 for protecting the hands, the other 34 for avoiding the penetration of dust or foreign bodies into the space left between prisms 29 and 30. Once the assembly has been effected, I place, on the periphery thereof, a holding ring 35 which is maintained by element 36.

The winding up and resetting to correct time are effected by means of suitable keys, engaging into holes 37, 38 of the back part of the watch according to the invention.

The watch, same as the clock above described, gives the same curious effect on one face as on the other.

In the case of a wrist watch (Figs. 13 to 16), there is a clockwork mechanism 39 the casing 40 of which is provided with two extensions 41 and 42 hinged at 41a and 42a and adapted to be tightly maintained by any suitable means such as, for instance, a screw in the position shown by Fig. 14. These extensions or lugs serve to the fixation of the wrist band 43. About casing 40 are fitted two glass or crystal blocks 44 and 45, substantially semi-circular shaped, the faces 46 and 47 of which are inclined in such manner as to form total reflection prisms. On the casing 40 are welded two substantially semi-circular elements, 48 and 49, the lower parts of which form two flanges 48a and 49a, the flange 48a maintaining the two plates 44 and 45 in position. After having placed the hands 50 and 51 and the dial 52 in position, the whole is surrounded by a glass or crystal box 53, which comes into engagement with flange 49a. Then the two extensions or lugs 41 and 42 are folded down and fixed through any suitable means, for instance a screw.

The winding up and setting to correct time take place as in the case of the watch above described. On the side of the structure turned toward the wrist, two holes 54 and 55 are provided for the introduction of suitable keys.

The watch which has just been described is mysterious only for an observer looking at the time on the dial. As a matter of fact, it is unnecessary to have the mystery effect on both sides, since the rear face of the watch is normally in contact with the wrist.

In a general manner, while I have, in the above description, disclosed what I deem to be practical and efficient embodiments of the present invention it should be well understood that I do not wish to be limited thereto as there might be changes made in the arrangement, disposition and form of the parts without departing from the principle of the present invention as comprehended within the scope of the appended claims.

What I claim is:

1. A time indicating device of the type described, which comprises, in combination, an annular dial, two time marking hands adapted to cooperate with said dial, a clockwork for actuating said hands, and at least two blocks of transparent material substantially surrounding at least the part of said clockwork which is connected with said hands, at least one of the faces of said blocks which are adjacent to said part of the clockwork being arranged to produce total reflection of the central visual rays substantially perpendicular to the dial of said time indicating device.

2. A time indicating device of the type described, which comprises, in combination, an annular dial; two time marking hands adapted to

cooperate with said dial, a clockwork for actuating said hands, and a system of blocks of transparent material assembled to form a housing for at least a part of said clockwork directly connected with said hands, the faces of said blocks that form the sides of said housing being arranged to produce total reflection of the visual rays from the front and the rear of said device.

3. A clock of the type described, which comprises, in combination, a base, an annular dial located above said base, transmission shafts extending upwardly from said base to said dial, two time marking means adapted to cooperate with said dial and operatively connected with said transmission shafts, a clockwork for operating said transmission shafts housed in said base, and a system of blocks of transparent material assembled to form a housing for said transmission shafts, the faces of said blocks that form the sides of said housing being adapted to produce total reflection of the visual rays from the front and the rear of said device.

4. A clock of the type described, which comprises, in combination, a base, an annular dial carried by said base above it, two time marking hands adapted to cooperate with said dial, a clockwork for operating said hands including a mainspring located in said base and a mechanism of elongated outer shape extending upwardly above said base, and a system of blocks of transparent material assembled together to form a housing for said mechanism, the faces of said blocks that form the walls of said housing being adapted to produce total reflection of the visual rays from the front and the rear of said clock.

5. A clock of the type described, which comprises, in combination, a base, an annular dial carried by said base above it, two time marking hands adapted to cooperate with said dial, a clockwork for operating said hands, including a barrel located in said base and a mechanism at least one part of which, of elongated outer shape extends vertically above said base, and a system of blocks of transparent material carried by said base, assembled together to form a housing for said elongated part of the clockwork mechanism, this system consisting of four blocks of trapezoidal horizontal section, said system having inner inclined faces on said blocks adapted to produce total reflection of the visual rays from the front and the rear of the clock.

6. A clock according to claim 5 further including two parallel mirrors parallel to the front face of the system of blocks.

7. A clock according to claim 5 further including a metallic casing surrounding said clockwork mechanism inside said blocks, said casing having at least two parallel reflecting faces perpendicular to the front face of the system of blocks.

8. A clock according to claim 5 further including a metallic reflecting casing surrounding said clockwork mechanism inside said blocks, said casing being of octagonal horizontal section with two opposed sides perpendicular to the front face of the system of blocks.

9. A clock of the type described, which comprises, in combination, a base, an annular dial carried by said base above it, two time marking hands adapted to cooperate with said dial, a clockwork for operating said hands, said clockwork including a barrel located in said base and a mechanism at least one part of which, of elongated outer shape, extends vertically above said base, a system of blocks of transparent material carried by said base, assembled together

to form a housing for said elongated part of the clockwork mechanism, this system consisting of four blocks of trapezoidal horizontal section, said system having inner inclined faces on said blocks adapted to produce, total reflection of the visual rays from the front and the rear of said clock, and an external casing surrounding said four blocks.

10. A clock of the type described, which comprises, in combination, a base, an annular dial carried by said base above it, two time marking hands adapted to cooperate with said dial, spindles for transmitting movement to said hands, a clockwork for operating said hands, said clock-

15 work including a barrel located in said base and a mechanism at least one part of which, of elongated outer shape, extends vertically above said base, and a system of blocks of transparent material carried by said base, assembled together to

20 form a housing for said elongated part of the clockwork mechanism, this system consisting of four blocks of trapezoidal horizontal section, said system having inner inclined surfaces on said blocks adapted to produce total reflection of the visual rays from the front and the rear of said clock, the front transparent blocks being mounted with a slight space between them forming a vertical slot for the passage of the spindles of said hands.

30 11. A clock according to claim 10, further including a small bar hiding said vertical slot.

12. A watch of the type described, which comprises, in combination, two hands for indicating the time, a spindle for said hands, a clockwork

35 for actuating said spindle and said hands, four blocks surrounding said clockwork, said four blocks being of transparent material and with bevelled edges so as to accommodate said clockwork, said edges being inclined to produce total reflection of the visual rays from the front and the rear of said watch, and a dial associated with said blocks and adapted to cooperate with said hands.

13. A watch of the type described, which comprises, in combination, two hands for indicating the time, spindles for said hands, a clockwork for actuating said spindles, four transparent blocks surrounding said clockwork, of substantially semi-circular shape and superposed two by

50 two, said blocks having bevelled edges so as to accommodate said clockwork, said bevelled edges being adapted to produce total reflection of the visual rays from the front and the rear of said watch, and a dial carried by said blocks and adapted to cooperate with said hands.

14. A watch of the type described, which comprises, in combination, two hands for indicating the time, spindles for said hands, a clockwork for actuating said spindles, a casing for said clock-

60 work having finely polished outer walls, four transparent blocks surrounding said clockwork and of substantially semi-circular shape and superposed two by two, said blocks having bevelled edges so as to accommodate said clockwork and to produce total reflection of the visual rays from the front and the rear of said clockwork, and a dial carried by said blocks and adapted to cooperate with said hands.

15. A watch of the type described, which comprises, in combination, two hands for indicating the time, spindles for said hands, a clockwork for actuating said spindles, a casning for said clockwork having finely polished external walls, four transparent blocks surrounding said clockwork, of substantially semi-circular shape and super-

posed two by two, said blocks having inner bevelled edges to accommodate said clockwork and to produce total reflection of the visual rays from the front and the rear of said clockwork, a dial carried by said block adapted to cooperate with said hands, and an annular holding element surrounding the whole of said blocks.

16. A watch of the type described, which comprises, in combination, two hands for indicating the time, spindles for said hands, a clockwork for actuating said spindles, a casing for said clockwork having finely polished external walls, a system of four transparent blocks surrounding said clockwork, of substantially semi-circular shape and superposed two by two, said blocks having inner bevelled edges to accommodate said clockwork and to produce total reflection of the visual rays from the front and from the rear of said clockwork, a dial carried by said blocks and adapted to cooperate with said hands, an annular holding element surrounding the whole of said blocks, and two protection glass plates on either side of said system of transparent blocks, respectively.

17. A watch of the type described, which comprises, in combination, two hands for indicating the time, spindles for said hands, a clockwork for actuating said spindles, a casing for said clockwork, two transparent substantially semi-circular shaped plates surrounding said clockwork, said plates having partially bevelled inclined edges to accommodate said clockwork and to produce total

reflection of the light rays from the front of said watch, and means forming a wrist band carrying said watch.

18. A watch of the type described, which comprises, in combination, two hands for indicating the time, spindles for said hands, a clockwork for driving said spindles, a casing for said clockwork having finely polished external walls, two transparent substantially semi-circular shaped plates surrounding said clockwork, said plates having partially bevelled inner edges to accommodate said clockwork and to produce total reflection of the light rays from the front and the rear of said clockwork, means for holding said transparent plates together, and a wrist band fixed to said last mentioned means.

19. A watch according to claim 18 further including a glass or crystal casing for protecting said dial.

20. A watch according to claim 18 in which the means for holding said plates together are hingedly connected to said clockwork casing.

21. A time indicating device comprising a substantially transparent face, time marking hands adapted to cooperate with said face, a clockwork for actuating said hands, and a body of substantially transparent material surrounding said hands, said body having means to produce total reflection of visual rays when the device is viewed from the front.

GASTON VICTOR GEORGES CUSIN.
